COMBINED MEMO PAD AND CALENDAR HOLDER

Richard N. Brandon, Louisville, Ky., assignor to Reynolds
Metals Company, Richmond, Va., a corporation of
Delaware

Application October 31, 1956, Serial No. 43,608

Term of patent 14 years

(Cl. D74—1)

The figure on the drawing is a front perspective view of a combined memo pad and calendar holder showing my new design. The rear hidden portion of the holder is unornamented.

The essential features of the design are shown in full lines. The dot and dash line showing of a memo pad is for illustrative purposes only.

I claim:

The ornamental design for a combined memo pad and calendar holder, substantially as shown and described.
